United States Patent Office.

ROBERT B. PARKINSON, OF PHILADELPHIA, PENNSYLVANIA.

Design No. 2,659, dated May 28, 1867.

DESIGN FOR A BOTTLE AND CAP.

The Schedule referred to in these Letters Patent and making part of the same.

TO ALL WHOM IT MAY CONCERN:

Be it known that I, R. B. PARKINSON, of Philadelphia, county of Philadelphia, State of Pennsylvania, have invented or produced a new and original Design for a Metal Bottle and Cap; and I do hereby declare that the accompanying drawing, and the following explanation thereof, form a full, clear, and exact description of the said design.

The figure in the accompanying drawing represents a metal bottle and cap, *a* being the cylindrical body of the bottle, and *b* the neck, which is of the form represented in the drawing. On the neck near the mouth of the bottle is a rib or "bead," *c*. A cap, *d*, which fits the neck above the rib *c*, is tapering in form, and is rounded at the top, as shown in the drawing.

Claim.

The design for a metal bottle and cap, substantially as shown in and by the accompanying drawing. In testimony whereof I have signed my name to this specification in the presence of two subscribing witnesses.

ROBT. B. PARKINSON.
